UNITED STATES PATENT OFFICE.

CHARLES SACKMAN, OF BROOKLYN, NEW YORK.

DESIGN FOR TEXTILE FABRIC.

SPECIFICATION forming part of Design No. 36,329, dated May 12, 1903.

Application filed March 20, 1903. Serial No. 148,796. Term of patent 3½ years.

● *To all whom it may concern:*

Be it known that I, CHARLES SACKMAN, a citizen of the United States, residing at 360 Macon street, borough of Brooklyn, county of 5 Kings, and State of New York, have invented a new, original, and ornamental Design for Textile Fabrics, of which the following is a specification, reference being had to the accompanying drawings, forming part thereof.

Figure 1 is a plan view of a fabric, showing my new design. Fig. 2 is a sectional view on the plane of the line 2 2 of Fig. 1, and Fig. 3 is a sectional view on the plane of the line 3 3 of Fig. 1.

My design is applied to a pile fabric, and, as shown in the drawings, the leading or material feature consists of a series of bands 1, intersecting each other at right angles and

dividing the fabric into blocks or sections 2. At the points of intersection of the bands 1 20 are portions 3. The sections 2 and portions 3 constitute the pile of the fabric and are raised or project above the bands 1.

Having described my invention, what I claim, and desire to secure by Letters Patent, 25 is—

The ornamental design for a textile fabric as herein shown and described.

In testimony whereof I have signed my name to this specification in the presence of 30 two subscribing witnesses.

CHARLES SACKMAN.
